FUEL MEASURING AND DISTRIBUTING
PUMP FOR OIL ENGINES

Frank David Butler, United States Navy

Application June 19, 1940, Serial No. 341,501

5 Claims. (Cl. 123—139)

(Granted under the act of March 3, 1883, as
amended April 30, 1928; 370 O. G. 757)

My present invention relates to a mechanism assembly as mentioned, the specific concepts of which contemplate the provision of the following: A multiple plunger delivery pump adapted to be driven from an anti-radial cam and to have a concentrically located rotary liquid fuel supply and discharge valve means, and a similarly controlled pressure means adapted to retain said plungers in contact with a cupped bearing ring resting on and operated by said cam; a vacuum means applied to the cam end of said plungers and adapted either to be used with or independent of said pressure means for retaining said plungers as mentioned; an additional safety plate adapted to secure said plungers to said bearing ring; a plunger type fuel supply pump adapted to be driven from said cam and similarly having such retainer means, valve control discharge means, and safety plate means, and to take suction from the source of fuel supply and to discharge into a reservoir forming a part of such assembly; a triangular shaped fuel measuring and distributing port adapted to be located in said rotary valve and to have its inward end in communication with a fuel pressure passage located within the latter, and its outer end terminating in the periphery of said valve and adapted (during the rotation of said valve) to form communication with a series of delivery ports located in the walls of the rotary valve chamber and each connected to its respective atomizer unit attached to the cylinders of such oil engine; adjustable means for longitudinally shifting said rotary valve within said valve chamber for varying the quantity of fuel distributed by said valve to said delivery ports through said triangular shaped port; a second adjustable means united with said first mentioned means and for circumferentially slightly rotating said valve chamber in relation to said triangular shaped port in order to advance or retard the timing of the distribution of the oil fuel by the latter; an adjustable relief valve means located within said rotary valve and adapted to relieve excess delivery fuel back into said reservoir; a spring loaded pressure limiting valve means adapted to close off the suction of said fuel supply pump when the pressure in said reservoir reaches a predetermined limit; and, various other minor improvement details in construction that will be pointed out hereinafter.

With reference to the drawings: Fig. 1 is a longitudinal section through the assembly mechanism of my invention and illustrates the rotary fuel delivery control valve in its mid-position of

longitudinal travel; Fig. 2 is a transverse section through the assembly on the levels 2—2 of Fig. 1; Fig. 3 is similar to Fig. 1 except with the moving elements of the assembly in a different position 5 of valve rotation and with the latter in its engine idling position of longitudinal travel; Fig. 4 is a transverse section of a portion of the assembly as it would appear on the level 4—4 of Fig. 3; Fig. 5 is similar to Fig. 4 except as would appear on the level 5—5 of Fig. 3; and Fig. 6 is similar to Figs. 4 and 5 except as would appear on the level 6—6 of Fig. 3.

With reference to the numerals of the drawings, the numeral 1 indicates the rotary valve member which is adapted to be a close slidable and rotatable fit within the concentric bore 2 of the combined fuel pump and distributor body 3, and to be rotated within said bore by the combined cam and drive shaft member 4 through the slidable coupling joint 5 located therebetween the upper end of the latter and the lower end thereof said valve member. The shaft 4 is adapted to be journalled in the bearing 6 which latter is located within the slightly rotatable housing 7 having the journal 8, and to be connected at the lower end thereof with a drive means (not illustrated) adapted to be operated from and in timing with the rotating elements of the oil engine to which the assembly is attached. The drive cam 9 is of the longitudinal (non-radial) type as illustrated and is integral with the shaft 4 and rests upon the lower thrust washer 10, has the upper thrust washer 11 inserted therebetween its upper cam surface and the lower surface of the annular and cupped shaped bearing ring 12 and is adapted to reciprocate the fuel supply pump plunger 13 and the plurality of fuel delivery pump plungers 14 vertically within their respective pump cylinders 15 and 16. The combined fuel pump and distributor body 3 is adapted to have a shouldered flanged joint fit concentric within the rotatable housing 7 and to be secured to the latter by the studs 17. The housing 7 in turn is adapted to be mounted within the casing 18 (forming a part of the engine housing or casing) in such a manner as to be slightly rotatable in either direction, being limited in such rotatable travel by the amount of relief given the ends of the semi-circular hole 19 in journal 8 as clearance to the bolt 20 which latter is adapted to clamp the casing 18 snugly about the journal 8.

The moving elements of the assembly within the housing 7 are adapted to be lubricated with

a heavy grade of lubricating oil or light grade of grease through the lubricating oil porting 21 located in parts 4, 9, 10, 11 and 12. Such lubricant being kept at a level in housing 1 approximately as illustrated in Figs. 1 and 3. The other moving elements of the assembly being lubricated by the oil fuel passing through such assembly. A slight vacuum being maintained inside of the lubricant well of housing 1 at the cam end of plungers 13 and 14 through tubing connections between fitting 22 and the engine intake manifold (the latter not illustrated) for purposes of retaining said plungers in a direction towards cam 9.

The fuel delivery plungers 14 are adapted (during their downward strokes) to take suction from the fuel reservoir 23 (surrounding the mid-section of the body 3) via the suction passages 24 connecting said reservoir with the bore 2, thence the fuel suction space 25 (located in 1 and adapted to intermittently connect said passages 24 with the delivery pump communication ports 26) and ports 26 (which latter extend between bore 2 and chambers 16) into the fuel delivery pump chambers 16 thereof such plungers 14. These plungers being adapted (during their upward strokes) to discharge this oil fuel in chambers 16 therefrom via said ports 26, thence the fuel discharge cavity 27 (located in 1 and adapted to be in communication with the fuel pressure chamber 28 internal to 1 via the radially extending port 29 likewise in 1) and into chamber 28 via port 29 as the cavity 27 intermittently forms communication with each of said ports 26. Simultaneously during the foregoing mentioned downward strokes of plungers 14, oil fuel from pressure chamber 28 is forced into the small cylinders 30 (one in tandem with each of chambers 16) above the small plungers 31 (one in tandem with each of the plungers 14) via the fuel pressure recess 32 (located in 1 and in communication with chamber 28 via access port 33) intermittently forming communication with the access passages 34 one extending between each of the cylinders 30 and bore 2. Likewise simultaneously during the foregoing mentioned upward strokes of plungers 14, this oil fuel in each of the cylinders 30 is forced therefrom via said passages 34 and thence the indenture 35 (located in 1 and adapted to intermittently connect said passages 34 and the radially extending passages 36 in body 3) and the passages 38, extending between bore 2 and the oil fuel reservoir 23, into the latter. Thus during the upward strokes of plungers 14 they are (in addition to the vacuum retainer means previously mentioned) forced and retained towards cam 9 by oil fuel under pressure in chambers 16, and during their downward strokes they are retained towards such cam by oil fuel under pressure in chambers 30.

The fuel supply pump plunger 13 is adapted (during its downward stroke) to take suction from the source of fuel supply via the fuel supply connection 37 and passages 38 (the former being located in the upper portion of housing 1 and the latter being located partly in such portion of said housing and partly in the lower portion of body 3) thence via the fuel supply passage 39 and fuel supply check-valve 40 (the former extending throughout the greater portion of the length of plunger 13 and the latter being located inside and in the vicinity of the upper end thereof of said plunger) and into the fuel supply pump chamber 41. While during the upward stroke thereof said plunger 13, this oil fuel in chamber 75

41 is discharged therefrom via the fuel communication port 42 (adapted to connect said chamber 41 with bore 2) into indenture 35 (as the latter forms communication between port 42 and the passages 36 at different levels in body 3) and thence via the passages 36 into the oil fuel reservoir 23. Simultaneously during the upward stroke of plunger 13, the oil fuel (previously admitted) above the shoulder 43 of plunger 13 in chamber 44 is discharged therefrom said chamber via the communication port 45 (extending between chamber 44 and bore 2) into said indenture 35 and thence (as the latter forms communication with said passages 36) via the passages 36 into the fuel reservoir 23. Simultaneously during the foregoing described downward stroke of plunger 13, oil fuel under pressure is forced from the pressure recess 32 (as the latter forms communication with port 45) via the port 45 into said chamber 44 above shoulder 43. Thus during the upward stroke of said plunger 13 it is (in addition to the vacuum retainer means previously mentioned) forced and retained towards cam 9 by oil fuel under pressure in chamber 41, and during its downward stroke it is retained towards such cam by oil fuel under pressure in chamber 44. As illustrated in Figs. 1 and 3, the cam ends of the plunger 13 and plungers 14 are equipped with ball shaped journals which are adapted to fit slightly loose laterally within suitable ball-sockets as illustrated in bearing ring 12, and are adapted to be secured in such ball-sockets by the safety plate 46 which is made in two semi-circular halves and are secured to ring 12 by screws 47 located as illustrated in Fig. 6. This safety plate 46 retains said plungers 14 and 13 in contact with ring 12 and either or both the vacuum and pressure retainer system or systems may be used to force or retain said plungers, the bearing ring 12 and the thrust slip ring 11 towards said cam 9.

The fuel supply pump assembly is equipped with an automatically operated cut out valve 48 having the resilient retainer spring 49 and valve stop pin 50 (as illustrated) and being adapted to close the suction passage 38 of such pump whenever the pressure on the oil fuel in reservoir 23 exceeds a predetermined limit. The fuel delivery pump system is likewise equipped with an excess pressure relief valve 51 having the resilient retainer spring 52 and adjustment screw 53 (all located within the upper portion of valve 1) and being adapted to relieve all excess oil fuel (above the setting of such valve) from fuel pressure chamber 28 to fuel reservoir 23 via the diagonally extending ports 54 (in 1 adjacent to 51), thence the annular shaped recess 55 in 1 and thence through the diagonally downward and outward extending port 56, leading from 55 to 23, into the latter.

The fuel distribution port 57 is triangular in shape and extends from the fuel pressure chamber 28 internal to the rotary valve 1 through and to the outer periphery of the latter and is adapted (during the rotation of the said valve 1) to intermittently and consecutively form communication with the series of fuel delivery ports 58 arranged in the same plane and thus disposed in the walls of bore 2 and connected to the engine fuel atomizers (not illustrated) in the proper firing sequence of such engine with the tubing connections 59. A plurality of pressure release grooves 55 and 60 are provided in valve 1, the former being located above and the latter below

the distributing port 57 and both being adapted to have communication with the fuel reservoir 23 and being in the form of leak-off porting means for the purpose of preventing slight fuel leakage from around the outer edges of distributor port 57 from accumulating pressure therebetween such grooves.

The rotary valve member 1 is equipped, at its extreme upward end, with the ball portion 61 which is adapted to fit rotatably within the ball-socket portion of the fuel delivery control treadle or handle 62 which latter has one end thereof adjustably fulcrum pivoted in the stanchion 63 on the adjustment bolt 64 having the butter-fly type clamping nut 65 with which latter to secure 62 tightly against 63. Such handle or treadle 62 being adapted to be retained in its full upward (or engine idling speed) position of travel by the resilient spring 66 (interposed between the lower side of 62 and the upper end of body 3), and to be limited in such upward travel by the low speed adjustment screw 67 striking a lug on 63. The shifting arrangement of the control treadle or handle 62 and the shape of the triangular fuel distribution port 57 being such that any vertical movement of 62 (and consequently port 57 with valve 1) will, during the rotation of valve 1, alter the length of each individual fuel delivery distribution period but will not alter the advance or retard of the commencement of such fuel delivery distribution period. While any lateral motion of control lever 62 (during the rotation of valve 1) will rotatably shift the body 3 in relation to valve 1 and distributing port 57 and will result in advancing (if moved against the rotation of shaft 4) or retarding (if moved in the direction of rotation of shaft 4) the entire fuel delivery distribution period but will neither increase or decrease the length of duration of such period. Hence the entire fuel delivery distribution and timing is controllable (and consequently the power output and timing of the engine) by and through manipulation of the single control lever 62. Should the control handle 62 (as illustrated in Fig. 3) be used, the adjustment bolt 64 and butterfly-nut 65 may be used to clamp the handle 62 in any position of elevation or depression, while the clamp bolt 26 may be used to clamp the journal 8 of housing 7 in any set position of advance or retard. However should the treadle 62 (as illustrated in Fig. 1) be used, then clamping of either 62 or 7 should normally be unnecessary. In the latter mentioned case the cleats 68 located on either side of treadle 62 may be used to move the latter laterally.

The annular shaped casing 23 of the fuel reservoir 23 may be made (as illustrated) of glass, or metal, in either case it is provided with packing 70 at either end thereof. This reservoir is provided with a drain plug connection system 71 (Fig. 2) which is arranged similar to that of fuel supply connection 37 and the vertically extending port 38 (Figs. 1 and 3).

The rotary valve member 1 is provided, at the upper end of distributor body 3, with a packing gland 72 adapted to prevent fuel leakage upward along said valve above said body 3.

The ball check-valve 40, of fuel supply pump plunger 13, is provided with a pin 73 which is secured in the upper end of said plunger 13 and is adapted to limit the lift of such valve 40 from its seat.

In regards to the manufacture of this type of assembly the following points should be kept in mind; inasmuch as the valve 1 rotates with cam 9, the valve cavities 25, 27, 32 and 36 in the former have (during the rotation of 1 and 9) a fixed circumferential relation with said cam and have no relation to the number of suction or delivery pump plungers; in order to maintain a non-fluctuating fuel delivery pressure, the minimum number of the fuel delivery plungers 14 per assembly should be three; in order to allow lap of the valve 1 over the ports 28, 34, 42 and 46 when the plungers 14 and 13 are at the extreme ends of their travel and without seriously 10 effecting or hindering such plungers on their upward stroke travel, the ratio between the circumferential travel of valve 1 and the lift of cam 9 should be relatively high; the number of the fuel delivery plungers 14 to the number of the cylinders of the engine have no relation one to the other; a plurality of fuel delivery distribution ports 57 located at different levels on the valve 1 and adapted to form communication with delivery ports 58 located likewise on different 20 levels in body 3 could be used if so desired; normally the number of the delivery ports 58 should equal the number of cylinders of the engine to which this assembly is attached; in two stroke cycle engines the shaft 4 should normally rotate at engine crank-shaft speed, while in the four stroke cycle engines the rotation of shaft 4 should be at one-half crank-shaft speed; if shaft 4 rotates at engine crank-shaft speed, then the circumferential width of distribution port 57 in degrees of a circle plus the similar width of one of the delivery ports 58 should normally equal the period in degrees of crank-shaft rotation of the duration of the fuel delivery; the amount of fuel delivered to the fuel atomizers during each 30 delivery period would depend upon several conditions the major ones of which are the length of such delivery period, the viscosity of the oil fuel, the pressure on said fuel, the size of the restriction in the delivery orifice 58 or therebeyond and the engine compression and combustion pressures; the object of providing either or both a vacuum and an oil pressure means for retaining plungers 14 and 13 normally in a direction towards cam 9 was to eliminate springs usually 40 provided for that purpose; normally parts identified by numerals 1, 3, 4, 5, 9, 10, 11, 12, 13 and 14 should all be made of some good grade of heat treated and hardened steel and should then have all their wearing surfaces ground to fit the adjacent wearing surfaces to close tolerance clearances; the valves 38 and 51 and the safety plate 46 should normally be made of a hard grade of 50 stainless steel metal; and, the control lever 62 should normally be made of a bearing bronze metal.

In regards to methods of accomplishing various results as described in the foregoing description of this assembly, the following facts are apparent therein and are therefore mentioned as a matter of record; in case the assembly is to be constructed to use the vacuum means only for retaining pistons 14 and 13 towards cam 9, then the pistons 31 and 43, chambers 38 and 44, communication ports or passages 34 and 45, recess 32 and access port 33 can all be eliminated and the plungers 14 and 13 with their respective cylinder chambers 16 and 41 can be relatively reduced in outside diameters, and in such case the 60 total cross-sectional area of said plungers at 70

their fits to said cylinder chambers should equal more than the cross-sectional area of the journal of said shaft 4 otherwise the shaft 4 will be drawn upward instead of plungers 13 and 14 downward towards cam 9 by such vacuum; on the other hand if recess 32 is eliminated (as just mentioned), then the port 57 should normally be located on the opposite side of valve 1 from fuel discharge cavity 27 so as to reduce as far as possible the lateral thrust of the discharge fuel on said valve; also in such case plungers 31 should be eliminated, then, if it were so desired, the plungers 14 could be equipped with fuel suction ball check-valves, ball limit lift pins, and fuel suction passages similar to 40, 73 and 39 respectively of plunger 13 and the fuel suction space 25 of valve 1 could then be eliminated and the fuel suction of said plungers 14 would be via said ball check-valve in lieu of space 25; on the other hand assuming it is not desired to extend the fuel suction ports 24 (as illustrated) from reservoir 23 to bore 2 via the recesses in plungers 14, then the lower end of space 25 could be machined in valve 1 so as to extend entirely therearound and in lieu of ports 24, one relatively large fuel suction port, adapted to extend directly between reservoir 23 and bore 2 and located between two of the chambers 16, could be used; it is known that the thrust washer 11 would not have to be applied between 9 and 12; it is also known that cam 9, washer 11 and ring 12 could be hardened and magnetized for purposes of retaining plungers 13 and 14 towards said cam; it is further known that lever 62 could be connected up to an ordinary rotating weighted governor if so desired; and, in the event that this assembly is to be applied to the power plant of a modern automobile, then the treadle control lever 62 should normally be located in the latter similar to and used in lieu of the present foot accelerator thereof for controlling such power plant.

The invention described herein may be manufactured and/or used by or for the Government of the United States of America for governmental purposes without the payment of any royalties thereon or therefor.

Having thus set forth and disclosed the nature of this invention, what I claim and desire to secure by Letters Patent is:

1. In a rotary drive combined fuel pump and distributing assembly having a plurality of axially disposed fuel delivery pump cylinders with cam operated reciprocating pump plungers therein symmetrically arranged about the axis of a rotary valve member operated through a slidably coupling by said rotary drive and slidably fitting within an elongated bore, the combination therewith of a fuel supply pump having an axially disposed pump cylinder with a pump plunger therein operated by said cam and connected to take fuel suction (by plunger displacement) from a source of fuel supply and to discharge such fuel via a recess in said rotary valve member into an annular shaped reservoir surrounding said pump cylinders, an access passage extending between said elongated bore and said reservoir, a plurality of ports one extending between each of said fuel delivery pump cylinders and said elongated bore, a cavity in said rotary valve member adapted to consecutively connect each of said ports with said access passage, an elongated fuel pressure compartment located within said rotary valve member, a concave located in the circumference of the latter and in communi-

cation with said fuel pressure compartment and adapted to consecutively connect each of said ports with said compartment, a plurality of radially extending fuel delivery orifices arranged symmetrically around said elongated bore, a tapering fuel distributing port located in the circumference of said rotary valve member and in communication with said fuel pressure compartment and adapted to consecutively connect each of said fuel delivery orifices with the latter, an adjustable pressure relief valve opening away from said fuel pressure compartment, fuel pressure release means in the form of two annular grooves located in the circumference of said rotary valve member one adjacent either end of said tapering fuel distribution port, a single manually controlled means for simultaneously moving said rotary valve member longitudinally in relation to said orifices and for circumferentially rotating said bore in relation to said tapering fuel distribution port, and, retrieving means for returning said plungers in a direction of travel towards said cam after having been forced away therefrom by the latter.

2. Claim 1 characterized by said retrieving means for returning said plungers in a direction of travel towards said cam to consist of a plurality of relatively small displacement retrieving plungers one in tandem with each of said pump plungers and each slidably fitting within a retrieving cylinder extending in tandem with each of said pump cylinders, and, means for supplying fuel under pressure from said fuel pressure compartment to each of said retrieving cylinders.

3. Claim 1 characterized by said retrieving means for returning said plungers in a direction of travel towards said cam to consist of a closed housing containing said cam and the drive ends of said pump plungers adjacent thereto, and, a connection access extending through said housing for coupling it to a vacuum means.

4. In an oil engine fuel pump and distributing assembly having a rotary drive shaft integral with an axially operating cam, and a rotary valve slidably coupled with and driven by said shaft and slidably mounted within an elongated bore, the combination therewith of a fuel supply pump cylinder having a retrieving pump cylinder in tandem therewith and axially disposed in relation to said rotary valve, a fuel supply pump plunger having a relatively small displacement retrieving pump plunger in tandem therewith and slidably fitting within said supply pump cylinder and retrieving pump cylinder and operable by said cam, a plurality of fuel delivery pump cylinders having each a relatively small bore retrieving pump cylinder in tandem therewith and axially disposed in relation to said rotary valve, a plurality of fuel delivery pump plungers each having a relatively small displacement retrieving pump plunger in tandem therewith and each slidably fitting within its respective fuel delivery pump cylinder with its tandem retrieving pump cylinder and operable by said cam, access port communication means through which to take suction with said fuel supply pump plunger from a source of fuel supply and through which to discharge said fuel via said rotary valve to a fuel reservoir surrounding all of said pump cylinders, an elongated fuel pressure compartment located within said rotary valve, access port communication means through which to take fuel suction with said fuel delivery pump plungers from said fuel reservoir via said rotary valve and through which to discharge such fuel via said rotary valve

into said fuel pressure compartment, means for supplying fuel under pressure from the latter to all of said retrieving pump cylinders, an adjustable pressure relief valve opening away from said fuel pressure compartment, a plurality of radially extending fuel delivery orifices arranged symmetrically around said elongated bore, a tapering fuel distribution port located in the circumference of said rotary valve and in communication with said fuel pressure compartment and adapted to consecutively connect each of said fuel delivery orifices with the latter, fuel pressure release means in the form of two annular shaped grooves located in the circumference of said rotary valve one adjacent either end of said tapering fuel distributing port and both having communication with said fuel reservoir, and, a single manually controlled means for simultaneously moving said rotary valve longitudinally in relation to said orifices and for circumferentially rotating said elongated bore in relation to said tapering fuel distributing port, or for independently performing either movement mentioned.

5. An oil engine fuel pressure pump having a plurality of cam operated fuel delivery pump plungers slidably mounted in a plurality of fuel

10 delivery pump cylinders of equal number to said fuel delivery pump plungers, means for supplying fuel to said pump cylinders and means for discharging said fuel from said pump cylinders under a pressure into a fuel pressure compartment, the combination therewith of a plurality of relatively small displacement retrieving pump plungers one in tandem with each of said fuel delivery pump plungers and each slidably mounted in a retrieving pump cylinder in tandem with each of said fuel delivery pump cylinders, a fuel supply pump plunger slidably mounted in a fuel supply pump cylinder and adapted to be operated by said cam, a relatively small displacement retrieving pump plunger in tandem with said fuel supply pump plunger and slidably mounted in a retrieving pump cylinder in tandem with said fuel supply pump cylinder, and, means for supplying fuel under pressure from said fuel pressure compartment into each of said retrieving pump cylinders adjacent said retrieving pump plungers for purposes of retaining all of said pump plungers in a direction of travel towards said cam.
